LEADER

Alfred W. Harse, Bellmore, N. Y.; Marie T. Harse
administratrix of said Alfred W. Harse, deceased

Application April 10, 1936, Serial No. 73,729

3 Claims. (Cl. 138—28)

This invention relates to leaders, an object of the invention being to provide a leader or analogous device which will permit of expansion and contraction thereof.

5 It is a well-known fact that in cold weather ice forms in leaders and the expansion within the leader causes the leader to burst, and it is a broad object of my invention to so construct the leader as to permit of the expansion of the 10 leader when ice forms therein and as the ice melts in the leader the latter will return to its normal size and shape.

Specifically, the invention includes a leader which is preferably, although not necessarily, 15 of general oblong shape in cross section with a gap in the back wall of the leader and an internal expandible member bridging said gap and springs connecting the sections of the back of the leader so that the leader is capable of repeated expansion and contraction without injury. Furthermore, the expandible member and 20 springs are at the back of the leader so that they are not seen and the leader has the ordinary appearance when in use.

25 With these and other objects in view, the invention consists in certain novel features of construction and combinations and arrangements of parts, all of which will be more fully hereinafter described and pointed out in the claims.

30 In the accompanying drawing—

Figure 1 is a perspective view illustrating my improved leader;

Fig. 2 is a view in transverse section through the leader;

35 Fig. 3 is a fragmentary view in longitudinal section on the line 3—3 of Fig. 2.

My improved leader indicated generally by the reference character A, is formed from a single sheet of proper metal and as illustrated in the 40 drawing is preferably, although not essentially, of general oblong shape in cross section. A gap illustrated generally by the reference character 1, is provided in the back of the leader and an internal expandible member 2 connects the sections of the back and coil springs 3 extend across the back and connect the sections at suitable intervals.

45 The specific construction illustrated may be defined as follows: A single piece of metal is bent to form the front wall 4, side walls 5, and back sections 6, and is then bent upon itself flat against the inner faces of the sections 6, as shown at 7, and the extremities of the sheet are then bent at an angle and extended toward each other and 50 connected by a proper seam 8, thus providing an

expandible member or bridge piece which is bowed, arched, or otherwise shaped in transverse section and extends inwardly of the leader. The back sections 6 and the portions 7 are perforated at suitable intervals, as shown at 9, to receive the hook ends 10 of the coil springs 3.

5 In operation when ice forms within the leader the expandible member 2 is forced rearwardly, that is, it is expanded transversely causing the back sections 6 and the sides 5 of the leader to 10 bow outwardly against the resistance of the coil springs 3, so that the expansion of the ice within the leader will not burst the same but is accommodated by the expansion of the leader. As the 15 ice melts in the leader the coil springs 3 draw the sections 6 toward each other and contract the leader to its normal shape and size. This 20 expansion and contraction can be repeated indefinitely without damaging the leader and without permanently changing its shape.

25 While I have illustrated what I believe to be a preferred embodiment of my invention, it is obvious that various changes might be made in the general form and arrangement of parts without departing from my invention, and hence I do 30 not limit myself to the precise details set forth but consider myself at liberty to make such changes and alterations as fairly fall within the spirit and scope of the appended claims.

I claim:

35 1. As a new article of manufacture, a leader having a gap in its wall, an internal expandible member bridging the gap, said expandible member curved in cross section and of greater width than the gap, and springs extending across the gap connecting the sections of the leader.

2. As a new article of manufacture, a leader having a gap in its back wall, an expandible member integral with the leader, curved in cross section, and located within the leader and bridging the gap between the sections of the leader, and coil springs extending across the gap and connected to the sections.

3. A leader composed of a single piece of metal bent to form flat sides and back sections spaced apart with a gap between them, the said sheet then bent flat against the inner faces of the sections and then arched or bowed inwardly and seamed together forming a curved expandible member, said back sections having openings therein, and coil springs extending across the gap and having their ends located in said openings.
